METHOD OF CONSTRUCTING HORIZONTAL
CYLINDRICAL TANKS

William A. Sandberg, Los Angeles, Calif., assignor to Lacy Manufacturing Company, Los Angeles, Calif., a corporation of California

Application March 19, 1940, Serial No. 324,837

3 Claims. (Cl. 29—148.2)

The invention relates to methods for constructing large cylindrical tanks in a horizontal position.

Tanks of this form, for the storage of light liquids or of compressed gases, have now attained great dimensions, as for example a diameter of thirty-two feet and a length of over two hundred feet, and the demand is for even larger tanks. Because of their size, which renders it impossible to move them any great distance, these containers must be constructed in the field, in the open air, and the methods conventionally used in the shop for the assembling of smaller cylinders either fail completely or become unduly costly when applied under field conditions.

Tanks of this type are customarily made up of a plurality of rings joined end to end, the longitudinal seams being staggered around the circumference and the heads being hemispherical or otherwise outwardly curved. They may be constructed with all the seams riveted, or with the longitudinal seams riveted and the round-about seams welded, or with all the seams welded, as may be preferred, all of these alternatives being found in prior practice. It is also well known to rotate the tank at intervals, during construction, to bring portions being worked on into convenient locations, particularly to bring seams to be welded into an approximately horizontal position.

The improvements making up the present invention comprise:

(a) The assembling of the tank from complete rings assembled and at least bolted up in a vertical position on the ground, stayed against deformation and thereafter lifted into the horizontal position;

(b) A novel method for staying the rings to prevent their deformation or collapse while being handled and assembled;

(c) A novel method and means for supporting the tank while under construction and for setting it accurately on its permanent foundations.

As the terms "vertical" and "horizontal" are likely to be confusing when applied to rings of which the diameter may be four or more times the length, it is premised that either term is applied herein solely to the cylindrical axis of the tank or to the ring rather than to the major dimension.

Wherever "girder" is referred to herein, reference is made to a circumferential girder, which may be inside or outside the shell.

These elements of novelty are shown and their 55 (preferably water) under pressure, as for exam-

advantages set forth in the accompanying drawings and the following description thereof, in which:

Fig. 1 is an elevation, on a minute scale, of a completed tank on its permanent foundations;

Fig. 2 is a plan view, on the same scale, showing the location on the jack foundations;

Fig. 3 is a fragmentary sectional view showing the location of the jacks as regards the circumference of the tank;

Fig. 4 is a diagram showing the manner of connecting the battery of jacks with the source of hydraulic fluid;

Fig. 5 is a sketch showing a single ring in the position in which it is constructed;

Fig. 6 is an end view of a ring illustrating the method of staying the rings against deformation;

Fig. 7 is a detail of a means for securing the ends of the stay rods to the ring, and

Fig. 8 is an elevation of a ring in position on the jacks and another ring approaching that position.

Referring first to Fig. 1, the completed tank indicated generally at 10 consists of a plurality of rings 11—11 and the heads 12—12. The tank is provided with brackets 13—13 resting on expansion rollers 14—14 which in turn rest on structural steel or other columns 15—15 supported by permanent concrete foundations 16—16. The tank is also provided with girders 36—36 which in this embodiment are shown as located inside the tank, though they may be placed outside if preferred.

The first step in the construction of a tank by the method herein proposed is to provide a plurality of jack foundations 17—17 spaced approximately as shown in Figs. 2 and 3. That is to say, the longitudinal spacing is such that the centers of the blocks coincide with the centers of length of the rings; the blocks are arranged in straight lines parallel to and equally spaced from the axis of the tank location, and the lateral spacing is such that the centre of the block is intersected by a radius which may be say 20°/30° from the vertical.

On each of the foundation blocks is placed a hydraulic jack 18 which preferably but not necessarily carries at its upper end a roller 19. These rollers, if used, facilitate the welding operation by permitting the tank to be rotated in the cradle formed by the two lines of rollers.

The entire assembly of jacks is connected as shown in Fig. 4 to any source of hydraulic fluid

ple a pump indicated at 20. A main hydraulic line 21 is branched as at 22-23 into two pairs of service branches 24-25 and 26-27, each of which should serve the same number of jacks. Each of these service lines should be valved when it leaves the branch 22 or 23, as indicated at 28, 29, 30, and 31, and it is convenient though not necessary to place valves 32 and 33 in these branches. Finally, each individual jack is provided with an inlet valve 34 and a bleeder valve 35. These are all manually operated valves, as for example globe valves or water cocks.

It is essential that all of the jacks be connected to a common source of supply, and it is also most desirable that all of the valves above described be provided. The purpose in placing all the jacks in communication, as they will be with all the valves except bleeder valves 35 open (their normal operating position) is to cause the jacks to exercise an equal lifting effect even though the 20 surface against which the rollers bear is out of round and/or out of alignment longitudinally, or in case individual foundation blocks should subside below their original level. This greatly reduces the cost of jack foundations as they can 25 be relatively light and shallow.

The four valves 28-31 have two uses. With all the jacks in communication, a temporarily unbalanced load such as may be produced by a concentration of workers or machinery in one 30 end of the shell may cause that end to subside below its normal level, correspondingly raising the other end. In such event the shell may be leveled by closing one pair of valves, as for example 29 and 31, leaving the corresponding pair open and feeding a small amount of hydraulic fluid, and again opening these valves after level 35 has thus been restored. Similarly, the shell may be moved over a short distance laterally by closing one pair of valves, as for example 30 and 31 40 and feeding hydraulic fluid through the opposite pair.

The individual inlet and bleeder valves 34 and 35 are used to collapse a single jack in order to pass it over an obstruction. For example, in rotating the tank, a butt strap or rivet head may engage a jack roller, and in such case a high rotating force is required to cause the roller to ride over the obstruction by displacing fluid into the remainder of the jacks. This application of force is avoided by closing valve 34 of this individual jack and opening bleeder valve 35, permitting the jack head and roller to subside and clear the obstruction. This also permits single jacks to be withdrawn for repairs.

If the permanent foundations are placed before the tank is constructed, as will often be found convenient, the jacks are set at such height that the tank constructed on them is clear of these foundations. If the main and service lines are laid and provided with valves, it is not necessary to put the jacks themselves into place until they are required, when they can be set in pairs as rings are ready to be placed on them, thus keeping the working space substantially clear.

The above described supporting and operating elements having been provided, the first step in the actual construction of the tank is to set up and stay the rings 11 of which it is composed, these rings being built one at a time as they are assembled to form the complete shell. This operation is performed on a reasonably level surface at or near ground level, the curved sheets being placed vertically to form the ring and the ends joined in the preferred manner, ordinarily by 70 75

riveted butt straps. Fig. 5 shows such a completed ring 11 with the stay rods in place.

When the ring proper is completed, it must be stayed to prevent deformation, as the ratio of ring diameter to sheet thickness is so great that the rings have no intrinsic stiffness whatever. Heretofore stays in compression—i. e., timber or steel braces—have been used for similar purposes, but the weight and cost are excessive, and I have substituted braces in tension with a highly material economy and an increased ease of handling. Diametric stay rods even if arranged of equal angles do not answer the purpose, as while such stays maintain opposite points of the circumference equally distant, they do not necessarily maintain the circular form; in fact if the ring be suspended at two points it assumes a pear-shaped outline which cannot be mated to the part of the shell already assembled. I have therefore devised the method of staying shown in Fig. 6.

In this structure, 37 is a centrally located disc of steel plate and 38-38 are radial tie rods welded or otherwise fastened to the plate as at 39. These rods may be threaded at their outer ends, passed through the clips 40 (Fig. 7), and tightened by means of nuts 41. The clips may be welded or bolted to the ring or, if preferred, the rod ends themselves may be welded lightly thereto. The radial angles should be equal and any desired number of stay rods may be used, in fact in very large rings it may be desirable to use two discs spaced one-third or one-half the length of the ring and a set of stay rods projected from each. This method of staying provides a ring which is stiff without being rigid; so that it may be lifted and swung into place without deforming while having enough local flexibility to permit it to be mated readily with the ring in place to which it is to be joined.

The next step in construction is to assemble the rings on the cradle formed by the jacks. Assembly may be started at any point along the length of the tank, usually at the end farthest from the ring assembling platform. A ring 11a is picked up by a crane, using the sling indicated at 42 in Fig. 8, is set in place on one pair of jacks (the inlet valves on all being closed), is lifted to the desired level for construction by manipulating the valves of the two jacks supporting it, and finally is guyed as at 43-43 in Fig. 8 to prevent it from overturning. The next ring 11b is then picked up and swung into place on the next pair of jacks and fastened to the first ring by the usual bolt clips 44, and this operation is repeated until the length of the shell is complete, admitting fluid to each pair of jacks as soon as the ring is in place over them. Only the first ring is guyed and the guys may be removed as soon as two or three rings are bolted together.

If it is desired to locate the girders inside the tank, as shown in this illustration, it is preferable to place them in the appropriate rings while the latter are being constructed on the ground. In such case the stays are omitted from the girder rings. If the girders are to be located outside the tank, all of the rings are stayed as shown and the girders are placed in the completed tank as below described.

When the cylindrical portion of the shell has been assembled and bolted up, the heads are placed and the tank is finished by any preferred riveting or welding operations. Ordinarily the longitudinal seams will have been finished in

advance and only the roundabout seams will remain to be formed. During this operation, and particularly when welding, it is desirable to rotate the tank on the cradle formed by the jack rollers, so as to bring the seams being worked on into the most convenient position. This may be done by means of an encircling cable and a winch. To avoid tipping of the jacks while rolling the tank on them, it is desirable to connect them in pairs by beams such as indicated at 45 in Fig. 3.

The tank is now tested for tightness, usually with air pressure, after which a part of the testing pressure is relieved and any external girders are placed and welded to the shell. The tank is then shifted, laterally and longitudinally as may be required, into its exact position over the permanent foundations, and is leveled. The brackets 13 and expansion rollers 14 are then put into place and the brackets fastened to the tank, or to the outer face of the girder, according to the location of the girder. Finally, the hydraulic pressure is removed from the jacks, which are withdrawn; the tank is deflated; and the stays and hub plates are removed through a manhole. The clips 40 may be left in position or knocked off as may be preferred, and the stays and hubs salvaged for use in succeeding constructions.

I claim as my invention:

1. The method of constructing horizontal cylindrical tanks of large diameter which comprises: constructing in an axially vertical position cylindrical rings having the diameter required for the tank by joining the straight ends of arcuately curved sheets; staying said rings to prevent deformation when said rings are lifted; lifting said rings to an axially horizontal posi-

tion, and assembling said rings end to end; resting each ring as assembled on two points of support; hydraulically applying a lifting effect to said supporting points as said rings are rested thereon and thereby bringing the adjacent ends of said rings into abutting position; joining said abutting ends to form a continuous cylinder and maintaining said lifting effects in hydraulic balance during said joining step to provide uniform support for said cylinder and prevent distortion thereof; attaching heads to the ends of said cylinder to form a substantially closed tank, and finally lowering said tank into its permanent position by withdrawing said hydraulic effect.

15 2. A method of staying cylindrical tank sections against deformation while assembling said sections to form a cylinder which comprises: extending radial tension members from a common center to substantially equally spaced points adjacent the inner wall of said section, and attaching the outer ends of said members to said wall in such manner as to place all of said members in substantially equal tension.

20 3. In a method of constructing horizontal cylindrical tanks which consists substantially in joining the ends of preformed and stayed cylindrical rings while said rings are assembled in end abutment and in axially horizontal position: the steps of resting each said ring during the 25 assembling operation on two points of support, of hydraulically applying a lifting effect to said supporting points to bring the ends of adjacent rings into register permitting them to be joined, and of maintaining said lifting effects in hydraulic balance until said tank is substantially completed.

WILLIAM A. SANDBERG.
